UNITED STATES PATENT OFFICE.

URIAH H. BALCOM, OF DOWNER'S GROVE, ILLINOIS.

WINDOW.

SPECIFICATION forming part of Letters Patent No. 267,820, dated November 21, 1882.

Application filed May 2, 1882. (No model.)

To all whom it may concern:

Be it known that I, URIAH H. BALCOM, of Downer's Grove, in the county of Du Page and State of Illinois, have invented certain new and useful Improvements in Windows; and I do hereby declare that the following is a full, clear, and exact description thereof, reference being had to the accompanying drawings, and to the letters of reference marked thereon, which form a part of this specification.

This invention relates to improvements in window frames and sash intended to be used in connection with outside blinds.

The object of the invention is to provide a construction in the frame for the admission of a full-length sash between the blinds and the divided or meeting sash, making a double window for winter use, and also to provide for the insertion of a screen for summer use in place of said outside sash.

The invention consists in features of construction in the window-frame and in the sash, and in the removable or interchangeable screen-sash, as will be hereinafter pointed out in the claims.

In the drawings, Figure 1 is a central vertical transverse section of the frame and sash, showing the full-length closed outer sash in position; and Fig. 2 is a similar section, showing the screen in place of the outer sash. Fig. 3 is an elevation of the outer winter-sash detached, showing the broad bottom rail, an aperture therein, and cover or slide for said aperture. Fig. 4 is an elevation of the screen detached, showing certain peculiar features of construction therein, by which the same is adapted for the improved frame herein described.

A A is the window-frame. B B are the outside blinds. C C' are the meeting-sash. D is the additional sash applied between the blinds and the windows C C', and E is a screen which in summer takes the place of the sash D.

For the purposes of this invention the frame A is provided with three removable stops, $a a'$ a^2 , in addition to the outside or blind stop, A'. This gives three sash-grooves, F, G, and G', in the latter two of which run the meeting-sash C and C'. In the outer of these grooves, F, the sash D, of the full length of the frame, is inserted from the inside after the removal of the stops $a a'$ a^2 and the interior meeting-sash, C C'. Said

sash D being full length, and therefore not adapted to be raised or lowered, and being used in connection with the outside blinds, B B, provision is made for reaching the blinds from the interior of the frame by providing said sash D with the broad bottom rail, D', in which is cut the aperture d, of sufficient size to allow the hand to be passed out through the same to reach and manipulate the blinds and their fastenings. The aperture d is covered or closed by any suitable form of slide or lid. In this case said lid consists of the thin gate D'', pivoted at d' on the inner face of the rail D', and is therefore adapted to be raised and lowered to open and close the aperture d. By this means the outer sash, D, is calculated to serve its purpose of affording additional protection from the weather, and at the same time it allows the blinds to be manipulated from the inside.

The screen E is not unlike ordinary screens, except that it is provided with the inner bead e at the top, securely fastened in place throughout its length, and also with the inner bead e' centrally pivoted to the screen-frame near the bottom. The object of the beads is obviously to close the space between the screen and the upper or outer of the two meeting-sash C, whether said screen occupy the upper or lower half of the window-frame. Said beads must of course be of such length as to entirely fill the space between opposite beads a. The object of pivoting the lower bead e' with the screen-frame is to enable the stops a to be inserted after said screen-sash is in place in the outer groove, for said bead, unless allowed to swing out of the way temporarily, being of the length required, would stand in the way of the stops a when being returned to their grooves and prevent their insertion. With the construction described it is only necessary to raise the screen-sash to the top of the frame, rotate the lower bead, e', on its central pivot, insert the stop a, upper end first, and then return the bead e' to its horizontal position. Said bead may be secured in this position until it is required to remove the screen by means of one or more screws or nails.

I am aware that it is a common thing to insert an outer continuous sash, corresponding in purpose with sash D, externally to the blind-stop and in the place of the blinds, and I am

also aware that it has been common to provide windows with double sets of sash or with four grooves for double sets of meeting-sash.

I am further aware that to a frame of ordinary construction—that is, having one set of meeting-sash—has been added a broad, separate, and removable inside stop contrived to support a second set of meeting-sash. These are not my invention, which consists in constructing the permanent frame A, having an outer or blind stop, A', with the three, and only three, grooves, F, G, and G', interior to said blind-stop, and with the permanent sash of the window fitted to and located in the two inner grooves, G and G', leaving the single outer groove, F, to be occupied as above set forth. This is a construction cheaply made, adapted to the usual depth of window-frames, and calculated to meet the requirements of both summer and winter by admitting either the full-length window-sash D or the screen-frame E without necessitating the removal of the blinds, if present. In other words, my invention consists in constructing the frame A to receive the usual pair of permanent meeting-sash C and C' farther inward than has been done in frames

intended for a single pair of such sash, and providing a single groove external thereto for the accommodation of said full-length outer sash and screen-frame.

30

I claim as my invention—

1. The window described, consisting of the frame A, provided with the blind-stop A' and the three inner sash stops, a, a', and a'', combined with the meeting-sash C and C', located 35 in the grooves G and G', and a single sash or frame in the groove F, substantially as described, and for the purposes set forth.

2. In combination with the frame provided with the three grooves F, G, and G', the blinds 40 B, and the meeting-sash C C', the outer sash, D, having the broad rail D', apertured to give passage to the hand, and provided with a closing slide, D'', substantially as described.

In testimony that I claim the foregoing as 45 my invention I affix my signature in presence of two witnesses.

URIAH H. BALCOM.
